UNITED STATES PATENT OFFICE.

EUGÈNE SCHNEIDER, OF PARIS, FRANCE.

GYROSCOPIC APPARATUS FOR THE DIRECTION OF SELF-PROPELLED TORPEDOES.

1,175,827.

Specification of Letters Patent. Patented Mar. 14, 1916.

Application filed April 9, 1915. Serial No. 20,358.

To all whom it may concern:

Be it known that I, EUGÈNE SCHNEIDER, a citizen of the Republic of France, resident of Paris, France, have invented a new and useful Improvement in Gyroscopic Apparatus for the Direction of Self-Propelled Torpedoes, which is fully set forth in the following specification.

As is well known self-propelled torpedoes are controlled by means of gyroscopes. An apparatus for the purpose comprises a spinning mass or "gyro-wheel" mounted in such a manner as to be adapted to move freely about one of its axes, (either by means of 15 equatorial rings or by any other means) the point of suspension being very near to the general center of gravity of the movable arrangement.

At the beginning of the course of the torpedo, the gyro-wheel is set in motion either by the impulse of a spring or by jets of compressed air acting on turbine blades or buckets (the latter being carried either by the gyro-wheel itself or by a separate turbine 25 wheel which is only in contact with the gyro-wheel during the very short period during which the latter wheel is set in motion).

The movement of the gyro-wheel in the first constructed apparatus, was not constant; the speed of rotation of the same gradually decreasing owing to the friction of its pivots and air resistance. In proportion to the increased distance traversed by the torpedo, it became necessary to maintain the speed of the gyro-wheel at an adequate value for a longer period of time. An advance has been made in this direction by increasing the initial speed of the gyro-wheel but 40 at the same time the resistance due to air friction increased and assumed very important values at high peripheral speeds of the gyro-wheel. Under these conditions, the initial increase of the speed of rotation was effective only during a very short period of time and the effective period of gyroscopic control did not increase in proportion to the complication and the weight resulting from the adoption of more powerful starting 45 means. It was therefore necessary to restore to the gyro-wheel in a continuous manner, the momentum absorbed by the various frictions and in order to provide continually the power absorbed in this manner, use 50 has been made either of a small electric motor keyed on the axis of the gyro-wheel, or of the action of air jets on blades or buck-

ets suitably disposed with respect to the gyro-wheel; these means for maintaining the movement being either capable or otherwise 60 of being combined with the means used for imparting to the gyro-wheel its initial impulse.

The apparatus forming the subject of the present invention has for its object to provide improvements in gyroscopic apparatus in which the movement is maintained by means of air jets.

The new apparatus permits of obtaining the following results:—1. The arrangement 70 of the apparatus is such that the action of the air jets maintaining the movement, does not produce any undesirable deviation of the gyroscopic apparatus. 2. Moreover, the entire arrangement is such that any inclination of the gyro-wheel with respect to the normal in the central plane of the vertical equatorial circle, is automatically corrected; such an inclination which can arise, for instance, from the friction of the valve controlled by the gyroscopic apparatus has a deleterious effect on the operation of the apparatus as it diminishes the tendency of the same to impose a constant average direction to the torpedo; in the case of an exaggeration 75 of this inclination, the direction of the torpedo would not be insured at all. In other words, the new apparatus has for its object to carry out automatically the correction of the position of the axis of the gyro-wheel in the case of an inclination, without 80 creating thereby deviations in the torpedo. 85

The invention is illustrated in the accompanying drawing, in which:—

Figure 1 is a section taken on the central plane of the vertical equatorial ring C. Fig. 2 is a section taken on the plane passing through the axis AB of oscillation of the vertical ring and through the axis XOX' of the gyro-wheel.

The vertical carrier ring C oscillates in known manner about pivots carried by the frame G of the apparatus. A conduit J formed in the frame G feeds in accordance with the invention, a circular groove M which is in permanent communication with the horizontal branch K of the elbow conduit K—K' the vertical branch of which is arranged according to the axis of the upper pivot C' of the vertical ring; the conduit K' opens into the conduit L formed in the thickness of the ring C, feeding the nozzles formed in the bosses I and I' provided in the said vertical ring. Whatever the posi-

tion of the vertical ring may be, air will reach through the groove M the conduit K—K' and thence the nozzles from which it will be projected onto the gyro-wheel H; 5 the central external surface of the latter is spherical in shape and buckets are formed on its rim. In accordance with the invention these buckets, the working surface α of which is plane, are also established in such 10 a manner that the plane of the surface α passes through the axis of the gyro-wheel XOX' and the depth p of each bucket is constant throughout the extent of the same.

The upper boss I is located with respect 15 to the movement of the gyro-wheel, laterally of the plane passing through the axis AB of the vertical ring and through the axis XOX' of the gyro-wheel so that the average direction i of the jet leaving the nozzle formed in the boss I passes through the uppermost point N of the average surface of the gyro-wheel; this condition is highly important from the point of view of the effect to be obtained. The nozzle formed in 20 the boss I' is located symmetrically with respect to the center of the vertical ring and its jet i' always acts on the lowermost point P of the average surface of the gyro-wheel. The horizontal ring F is mounted in known 25 manner with respect to the vertical ring C and the gyro-wheel H.

The operation is as follows:—The jets of air leaving the nozzles formed in the bosses I and I' produce reactions on the vertical 30 ring; which reactions owing to the disposition of the jets in the same symmetrical plane of the vertical ring are operative in the same plane, are absorbed by the pivots of the vertical ring and do not interfere in the 35 least with the operation of the gyroscope. On striking the buckets, the air jets produce movements normal to the buckets and as the same are plane and pass through the axis of the gyro-wheel, the action of the air jets can 40 be expressed as a force which is always in the plane of symmetry of the vertical ring. Normally, the points of application of the two equal and opposite forces are the points N and P (the uppermost and lowermost) 45 and their average directions are N—Q and P—R horizontal tangents to the circle cut in the central surface of the gyro-wheel by the plane of symmetry of the vertical ring in which the gyro-wheel is suspended. 50 It will be seen that the forces N—Q and P—R have for their effect to maintain the movement of the gyro-wheel by creating a couple around the axis XOX'. Moreover, 55 these forces cannot create any undesirable deviation of the gyro-wheel. In fact, by virtue of the properties of rapidly rotating bodies, a rotation of the gyro-wheel around the axis AB could only be produced by forces having a certain moment about the 60 axle DE; the forces N—Q and P—R, how- 65

ever, are parallel to DE and it follows that the deviation around the axis AB is always zero. On the contrary, in the case of the inclination of the gyro-wheel as illustrated in Fig. 2, the forces which are projected at N 70 and P on Fig. 2, have a certain moment with respect to the axis SS' located in the plane of Fig. 2; it can be seen that this moment is of a nature to cause the axis XOX' to re-assume a position at right angles to the 75 axis AB, without producing a rotation about the axis AB.

With buckets as here shown, if the points of impact of the air jets were not located at the uppermost and lowermost points N 80 and P while remaining symmetrical, the above result would not be attained in the case of an inclination; the actions on the buckets of the gyro-wheel (actions always located in a plane normal to the axis XOX') 85 would have a certain moment with respect to the axis DE and this would result, always according to the properties of rapidly rotating bodies, in a deviation about the axis AB of the vertical ring. However if the 90 two points of impact were located on the axis DE of the horizontal ring, there would be no deviation about the axis AB but the automatic correction in the case of an inclination relatively to the horizontal would 95 no longer be produced.

What I claim and desire to secure by Letters Patent of the United States is:—

1. The combination of a carrier-ring pivoted for movement about a diametral axis, 100 an equatorial ring pivotally mounted on the carrier-ring for movement about a diametral axis perpendicular to the said diametral axis of the carrier-ring, a gyro-wheel supported by the equatorial ring and rotatable about an axis perpendicular to the said diametral axes and provided with peripheral buckets, and nozzles positioned to deliver jets of fluid against the buckets at such points and in such directions that 110 they rotate the gyro-wheel on its axis and tend to hold it against movement about the diametral axis of the equatorial ring.

2. The combination of a carrier-ring pivoted for movement about a diametral axis, 115 an equatorial ring pivotally mounted on the carrier-ring for movement about a diametral axis perpendicular to the said diametral axis of the carrier-ring, a gyro-wheel supported by the equatorial ring and rotatable about an axis perpendicular to the said diametral axes and provided with peripheral buckets, and nozzles remote from the plane 120 of the equatorial ring for delivering jets of fluid directly into the openings of the buckets with the gyro-wheel in any of a plurality of positions of adjustment about the said diametral axis of the equatorial ring.

3. The combination of a carrier-ring piv- 130

- oted for movement about a diametral axis, an equatorial ring pivotally mounted on the carrier-ring for movement about a diametral axis perpendicular to the said diametral axis 5 of the carrier-ring, a gyro-wheel supported by the equatorial ring and rotatable about an axis perpendicular to the said diametral axes and provided with transverse pivotal buckets curved inward at their ends and 10 each lying in a plane containing the gyro-wheel axis, and nozzles positioned to deliver jets of fluid against the buckets.
4. The combination of a carrier-ring pivoted for movement about a diametral axis, 15 an equatorial ring pivotally mounted on the carrier-ring for movement about a diametral axis perpendicular to the said diametral axis of the carrier-ring, a gyro-wheel supported by the equatorial ring and rotatable 20 about an axis perpendicular to the said diametral axes and provided with transverse peripheral buckets curved inward at their ends and each lying in a plane containing the gyro-wheel axis, and nozzles supported 25 independently of the equatorial ring and positioned to deliver jets of fluid against the buckets.
5. The combination of a carrier-ring pivoted for movement about a diametral axis, 30 an equatorial ring pivotally mounted on the carrier-ring for movement about a diametrical axis perpendicular to the said diametral axis of the carrier-ring, a gyro-wheel supported by the equatorial ring and 35 rotatable about an axis perpendicular to the said diametral axes and provided with transverse pivotal buckets curved inward at their ends, and nozzles positioned to deliver jets of fluid against the buckets at points re- 40 mote from the said diametral axis of the equatorial ring.
6. The combination of a carrier-ring pivoted for movement about a diametral axis, an equatorial ring pivotally mounted on the 45 carrier-ring for movement about a diametral axis perpendicular to the said diametral axis of the carrier-ring, a gyro-wheel supported by the equatorial ring and rotatable about an axis perpendicular to the said diametral axes and provided with transverse pivotal buckets curved inward at their ends, and nozzles positioned to deliver jets of fluid against the buckets at points lying in a plane perpendicular to the plane of the 55 equatorial ring and passing through the axis of the gyro-wheel.
7. The combination of a carrier-ring pivoted for movement about a diametral axis, an equatorial ring pivotally mounted on the 60 carrier-ring for movement about a diametral axis perpendicular to the said diametral axis of the carrier-ring, a gyro-wheel supported by the equatorial ring and rotatable
- about an axis perpendicular to the said diametral axes and provided with transverse 65 peripheral buckets curved to conform to a sphere having its center at the intersection of the aforesaid axes, and nozzles positioned to deliver jets of fluid against the buckets at points remote from the common plane of 70 the said diametral axis of the equatorial ring and the axis of the gyro-wheel.
8. The combination of a carrier-ring pivoted for movement about a diametral axis, an equatorial ring pivotally mounted on the 75 carrier-ring for movement about a diametral axis perpendicular to the said diametral axis of the carrier-ring, a gyro-wheel supported by the equatorial ring and rotatable about an axis perpendicular to the said diametral axes and provided with transverse 80 peripheral buckets curved to conform to a sphere having its center at the intersection of the aforesaid axes, and nozzles positioned to deliver jets of fluid against the buckets 85 at points lying in a plane perpendicular to the plane of the equatorial ring and passing through the axis of the gyro-wheel.
9. The combination of a carrier-ring pivoted for movement about a diametral axis, 90 an equatorial ring pivotally mounted on the carrier-ring for movement about a diametral axis perpendicular to the said diametral axis of the carrier ring, a gyro-wheel supported by the equatorial ring and rotatable 95 about an axis perpendicular to both of the said diametral axes and provided with transverse peripheral buckets curved inward at their ends, and nozzles fixedly mounted on the carrier ring at points remote from 100 the diametral axis of the equatorial ring and positioned to deliver jets of fluid against the buckets.
10. The combination of a carrier ring pivoted for movement about a diametral axis, an equatorial ring pivotally mounted on the carrier-ring for movement about a diametral axis perpendicular to the said diametral axis of the carrier ring, a gyro-wheel supported by the equatorial ring and 110 rotatable about an axis perpendicular to both of the said diametral axes and provided with transverse peripheral buckets curved inward at their ends, and nozzles fixedly mounted on the carrier ring and positioned 115 to deliver jets of fluid against the buckets at points in the said diametral axis of the carrier ring.
